UNITED STATES PATENT OFFICE.

WILLIAM H. PAGE, OF NORWICH, CONNECTICUT, ASSIGNOR TO WILLIAM H. PAGE & CO., OF SAME PLACE.

DESIGN FOR PRINTING-TYPE.

Specification forming part of Design No. 7,229, dated March 3, 1874; application filed January 5, 1874.
[Term of Patent 7 years.]

To all whom it may concern:

Be it known that I, WILLIAM H. PAGE, of Norwich, in New London county and State of Connecticut, have invented a Design for Printing-Types, of which the following is a specification:

The nature of my design is fully represented in the accompanying printed illustration, to which reference is made.

This design of letters has several novel and peculiar features, there being the projections or ornaments upon the center of the sides of the letters, consisting of two small sharp curves turned outward from the side of the letter, and connected by a straight line; also, the various figures upon the face of the letters,

as shown; and the terminations of the C and other similar parts have a double bevel at the end. These letters also have their ceriphs heavy, with their ends beveled and converging outward, and the letters are also heavily shaded throughout.

I claim as my invention—

The design for an alphabet of letters, having the side ornaments, and figures upon their faces; also, the shade and the beveled ceriphs and terminations, substantially as herein shown and described.

WILLIAM H. PAGE.
